Fig. 5

Fig. 6Fig. 7Fig. 8Fig. 9FIGURE 1 is a top plan view of a laboratory tray for making microtitrations, growing cultures, and the like, showing our new design;

FIGURE 2 is a bottom view thereof;

FIGURE 3 is a side view thereof;

FIGURE 4 is an end view thereof;

FIGURE 5 is a fragmentary sectional view thereof taken substantially along the line 5—5 of FIGURE 3;

FIGURE 6 is a top plan view of a laboratory plate similar to that illustrated in FIGURES 1—5 inclusive but embodying substantially conically shaped end wall cups and constituting a second embodiment of this invention;

FIGURE 7 is a bottom view thereof;

FIGURE 8 is a side view thereof;

FIGURE 9 is an end view thereof;

FIGURE 10 is a fragmentary sectional view thereof taken substantially along the line 10—10 of FIGURE 8.

The characteristic feature of our design resides in the specific uniformly elongated configuration of identi-

cal cup members in association with a tray member as best illustrated in FIGURES 3, 4, 8 and 9.

We claim:

The ornamental design for a laboratory tray for making microtitrations, growing cultures, and the like, substantially as shown and described.
